UNITED STATES PATENT OFFICE.

JOHN McMULLEN, OF BUFFALO, NEW YORK.

HOPPER-CAR DOOR.

Application filed September 29, 1925. Serial No. 59,408.

This invention relates to railway cars of the type more particularly known as dump cars which have drop doors hinged to the underframe and extending beneath certain members of the car, and the invention has for its object to improve the construction of such cars by providing means for minimizing leakage of material therefrom, and for strengthening the doors so as to adapt the cars to meet the various requirements for successful commercial operation.

The object of the invention is to stiffen the corner or corners of the door, as any bending or drooping of the corners would cause a leak of the lading, especially of such fine material as sand, chats, etc. Any bending or warping might interfere with the complete closing or locking of the door.

In the drawings:

20 Fig. 1 shows a hopper door with my reinforcement having my approved construction.

Fig. 2 is a side elevation of Fig. 1.

25 Fig. 3 is a section on line 3—3 of Fig. 1. Fig. 4 shows a modified form of my invention.

Fig. 5 is a section on line 5—5 of Fig. 4.

30 Fig. 6 is similar to Fig. 3 but shows the embossment projecting upwardly.

The door is made of a metallic plate (preferably steel) having flanges 2—3 (preferably continuous) on all of its sides which strengthen the door to carry the lading. The corners of the door are stiffened by an embossment near the adjacent side of the flanges (or bend of a continuous flange) which stiffen the corner of the door against drooping or bending; for instance, on lines 35 parallel to line 6—6 in Fig. 1 or line 7—7 in Fig. 4.

In the construction shown in Figs. 1 to 3, inclusive, the embossment comprises two portions 8—9, each adjacent one side of the door, which portions are widest at their juncture 10 and taper towards their ends 11—12.

50 In the modification shown in Figs. 4 and 5 the embossment 13 is positioned so as to substantially bisect the angle of the corner of the door and is widest (14) adjacent the end 15 nearer to the corner of the door, and two of its sides are substantially parallel to the corresponding sides of the door.

55 The embossments preferably project upwardly but may be pressed downwardly and come within the scope of the invention.

Downwardly projecting embossments should be provided with drain holes 16.

The embossments may be used in the outer corners only or the inner corners only or in all four corners, if desired.

I claim:

1. A metallic door for a railway dump car formed of a metallic plate having flanges on its adjacent sides, and an embossment in the corner adjacent to said flanges, the opposite ends of said portions merging into the plane of the plate.

2. A metallic door for a railway dump car formed of a metallic plate having flanges on its adjacent sides, and an embossment in the corner comprising portions parallel to and adjacent to each of said flanges, the opposite ends of said portions merging into the plane of the plate.

3. A metallic door for a railway dump car formed of a metallic plate having flanges on its adjacent sides, and an embossment in the corner comprising portions parallel to and adjacent to each of said flanges, the opposite ends of said portions merging into the plane of the plate, said embossment being widest at the juncture of said portions and tapering toward their ends.

4. A metallic door for a railway dump car formed of a metallic plate having flanges on its adjacent sides, and an embossment in each of its corners comprising portions parallel to and adjacent to each of said flanges, the opposite ends of said portions merging into the plane of the plate.

5. A metallic door for a railway dump car formed of a metallic plate having flanges on its adjacent sides, and an embossment in each of its corners comprising portions parallel to and adjacent to each of said flanges, the opposite ends of said portions merging into the plane of the plate.

6. A metallic door for a railway dump car formed of a metallic plate having flanges on its adjacent sides, and an embossment in each of its corners comprising portions parallel to and adjacent to each of said flanges, the opposite ends of said portions merging into the plane of the plate, said embossment being widest at the juncture of said portions and tapering toward their ends.

7. A metallic door for a railway dump car formed of a metallic plate having a continuous flange on its adjacent sides, and an embossment in the corner comprising portions parallel to and adjacent to said flange,

the opposite ends of said portions merging into the plane of the plate.

8. A metallic door for a railway dump car formed of a metallic plate having a continuous flange on its adjacent sides, and an embossment in the corner comprising portions parallel to and adjacent to said flange, the opposite ends of said portions merging into the plane of the plate, said embossment being widest at the juncture of said portions and tapering toward their ends.

9. A metallic door for a railway dump car formed of a metallic plate having an embossment in the corner comprising portions parallel to and adjacent to the sides of the door, said embossment being widest at the juncture of said portions and tapering toward their ends.

10. A metallic door for a railway dump car formed of a metallic plate having an embossment in the corner comprising portions parallel to and adjacent to the sides of the door, said embossment being widest and deepest at the juncture of said portions and tapering toward their ends.

11. A metallic door for a railway car

formed of a metallic plate having flanges on its adjacent sides, and an embossment with its opposite ends merging into the plate and having its longitudinal axis bisecting the corner formed by the flanges and being widest adjacent said corner.

12. A metallic door for a railway car formed of a metallic plate having flanges on its adjacent sides, and an embossment with its opposite ends merging into the plate and having its longitudinal axis bisecting the corner formed by the flanges and being widest and deepest adjacent said corner.

13. A metallic door for a railway car formed of a metallic plate having an embossment with its opposite ends merging into the plate and having its longitudinal axis bisecting the corner of the door and being widest adjacent said corner.

14. A metallic door for a railway car formed of a metallic plate having an embossment with its opposite ends merging into the plate and having its longitudinal axis bisecting the corner of the door and being widest and deepest adjacent said corner.

JOHN McMULLEN.
